Specification for Design.

Patented Apr. 4, 1911.

Application filed April 14, 1910. Serial No. 555,547. Term of patent 7 years.

To all whom it may concern:

Be it known that we, HERMAN C. STROBEL and LORENZ KILLIAN, citizens of the United States, residing at New York, in the county of New York and State of New York, and Brooklyn, in the county of Kings and State of New York, have invented and produced a new, original, and ornamental Design for a Table, of which the following is a specification, reference being had to the accompanying drawing, forming a part thereof.

The invention consists in the spindle or column supporting a plain round table top, the spindle being provided with a rib intermediate the table and the base, such base

being formed octagonal with conventional leaves extending from the connection with the spindle downwardly in curved lines and increasing in width to an octagonal shoulder spaced away from the periphery of the octagonal base member.

We claim,

The ornamental design for a table as shown and described.

HERMAN C. STROBEL.
